(57) CLAIM

The ornamental design for the chair, as shown and described.

DESCRIPTION

FIG. 1 is an upper perspective view of the chair showing my design.

FIG. 2 is a front view thereof;

FIG. 3 is a back view thereof;

FIG. 4 is a side view thereof;

FIG. 5 is an opposite side view thereof;

FIG. 6 is a top plan view thereof;

FIG. 7 is a bottom plan view thereof; and,

FIG. 8 is another opposite side view thereof, showing a stacked position in broken lines.

The broken lines are presented for illustrative purposes only and form no part of the claimed design.
